229,092

COMBINED WEIGHING SCALE, TAPE MEASURE AND FISHHOOK REMOVER

Michel Quenot, Zone Industrielle Trepillot,
Besancon, France

Filed Jan. 5, 1972, Ser. No. 215,695

Claims priority, application France July 12, 1971

Term of patent 14 years

Int. Cl. D10—04

U.S. Cl. D52—1 R

FIG. 1

FIG. 2

FIG. 1 is a front perspective view of a combined weighing scale, tape measure and a fishhook remover showing my new design.

FIG. 2 is a back perspective view thereof showing the tape and scale hook in closed position.

I claim:

The ornamental design of a combined weighing scale, tape measure and fishhook remover, substantially as shown.
